United States Patent Office

Des. 203,293

Patented Dec. 21, 1965

203,293

LUMINAIRE

Myron F. Pettengill, Hendersonville, N.C., assignor to
General Electric Company, a corporation of New York

Filed June 12, 1964, Ser. No. 80,367

Term of patent 14 years

(Cl. D48—31)

Fig.1.

Fig.2.

Fig.3.

FIGURE 1 is a top plan view of a luminaire embodying my new design;

FIGURE 2 is an elevational view thereof; and

FIGURE 3 is a bottom plan view thereof.

The broken lines are shown for illustrative purposes only.

I claim:

The ornamental design for a luminaire, as shown.
